UNITED STATES PATENT OFFICE.

JOHN M. FOSTER, OF FULTON, NEW YORK.

POWDER BOX AND PUFF.

Application filed August 9, 1921. Serial No. 490,934.

To all whom it may concern:

Be it known that I, JOHN M. FOSTER, a citizen of the United States, residing at Fulton, in the county of Oswego and State of New York, have invented certain new and useful Improvements in Powder Boxes and Puffs, of which the following is a specification.

This invention relates to new and useful improvements in talcum powder containers and means associated therewith for applying the powder as desired.

Another object of the invention is to provide a powder container having a combined closure and powder puff and means for causing the powder in the container to be sprinkled upon the puff when the container is inverted.

Other objects and advantages of the invention will become apparent during the course of the following description.

In the accompanying drawings forming a part of the specification and wherein like numerals are employed to designate like parts throughout the several views.

Figure 1 is a side elevation of the container with the upper end thereof broken away,

Figure 2 is a bottom plan of the closure, and

Figure 3 is a top plan of the container with the closure removed.

Referring to the drawing wherein for the purpose of illustration is shown the preferred embodiment of my invention, the numeral 4 designates a container for powder or any other toilet preparation, and in the present instant is illustrated as being of elliptical cross section, but it is of course to be understood that the shape of the container may be varied without departing from the spirit of the invention. The bottom of the container is of course closed in the well known manner, while the top is open and an outwardly projecting bead 5 is pressed from the container adjacent its upper end to form a groove on the interior of the receptacle which extends entirely around the same. A partition or plate 6 having perforations 7 in its central portion is arranged horizontally within the receptacle adjacent its upper end and has its edges snapped into the groove formed by the bead 5.

The closure for the receptacle consists of a cap 8 having a depending flange 9 extend-

ing therefrom so that the top of the receptacle may be snugly fitted onto the closure whereby the latter will be retained upon the container and precluded from accidental displacement therefrom. However, it is to be understood that the closure has a sliding fit with the container so that it may be readily removed as will be explained hereinafter. The closure 8 is provided with an aperture in the center thereof for the passage of a screw 10. This screw has its head embedded in the back 11 of a powder puff while the pointed end of the screw threads into a knob or handle 12 extended upwardly from the center portion of the closure and exteriorly thereof.

A powder puff 13 consisting of chamois, cotton or any other suitable material is secured to the underface of the back 11 by gluing or any other suitable means and when the closure 8 is positioned upon the container to close the same, the powder puff is disposed in close proximity to the plate or partition 6 directly above the apertures 7 therein. Referring to Figure 2, it will be noted that the powder puff and its back 11 are of substantially the same shape as the closure but are considerably smaller than the closure so that the edge of the powder puff and its back will be spaced from the depending flange 9 of the closure to admit of the upper end of the container passing well up into the closure between the back of the powder puff and the flange 9.

When it is desired to use the powder puff, the container is inverted to cause the powder therein to fall against the partition 6 and to sift through the apertures 7 upon the powder puff 13. The container is then stood upon its bottom while the closure 8 is removed by means of the knob 12 and the powder on the puff applied as desired, it being understood that the puff 13 is disposed well beyond the bottom of the closure as clearly seen. However, when it is merely desired to sift some of the powder from the container, the closure is simply lifted off and the container moved back and forth to cause the powder therein to fall through the apertures 7 in the plate 6.

In view of the fact that the perforated partition 6 is disposed below the top of the container, no powder remaining upon the partition around the apertures therein will be wasted after the container has been used, for the powder will simply remain on

the partition and be taken up by the powder puff when the closure is repositioned upon the container. As the parts of the powder puff are readily detachable, it will be obvious that the puff may be renewed from time to time and used in conjunction with other powder containers when the supply in the original container has been exhausted.

19 The foregoing description and accompanying drawings have reference to what might be considered to be the approved or preferred form of my invention. I desire it to be understood that I may make such 15 changes in the construction, combination and arrangement of parts material, dimensions, etc. as may prove expedient and fall within the scope of the appended claim.

Having thus described my invention, 20 what I claim as new and desire to secure by Letters Patent is:

In a powder dispensing device, the combination with a powder box including a

body having an open upper end, a perforated partition plate disposed in the body 25 forming a powder supply compartment and a powder dispensing compartment, and a cover for the open end of the box having an axial opening therein, of a powder puff associated with the cover adapted to extend 30 into the powder dispensing compartment including a rigid back engaging the cover and closing the opening therein, a knob associated with the cover including an enlarged base extending through the opening 35 in the cover and engaging the back of the powder puff, and a single fastening element extended through the back of the powder puff into the knob for firmly binding the 40 knob, powder puff and cover together.

In testimony whereof I affix my signature in presence of two witnesses.

JOHN M. FOSTER.
